UNITED STATES PATENT OFFICE.

MATHIAS WEIWODA, OF NEW YORK, N. Y., ASSIGNOR TO GEORGE W. STEVENS, OF NEW YORK, N. Y.

CARBURETER.

1,009,121.

Specification of Letters Patent. Patented Nov. 21, 1911.

Application filed February 20, 1909. Serial No. 479,045

To all whom it may concern:

Be it known that I, MATHIAS W LIWODA, a citizen of the United States, and a resident of the city of New York, borough of Brooklyn, in the county of Kings and State of New York, have invented a new and Improved Carbureter, of which the following is a full, clear, and exact description.

This invention relates to certain improvements in carburetors for forming explosive mixture, and more particularly to that type of carburetor in which a liquid fuel is used and which is vaporized and mixed with air or other oxygen-bearing gas.

15 The subject-matter disclosed in this application has been made the basis of an application for throttle valve for carbureters, Serial No. 543,913, filed February 15, 1910, and an application for float valve for carbureters, Serial No. 543,959, filed February 15, 1910.

One important feature of my carburetor involves a construction whereby there is a thorough and uniform mixing of the air and liquid fuel. The air is delivered to the liquid below the surface thereof and becomes charged not only in passing through the liquid but also in passing over the surface of plates wet with liquid drawn up by capillary attraction.

A further important feature resides in the means for insuring a uniform distribution of the air over the surface of said moistened plates.

5 My improved carbureter is illustrated as
being provided with improved means for
controlling the delivery of the fuel to the
vaporizing chamber; for controlling the de-
livery of the carbureted mixture from the
6 carbureter; for automatically diluting the
same, and for accomplishing various other
desirable objects. These means are covered
in my two divisional applications.

My invention involves various other features of greater or lesser importance, which will be hereinafter referred to and defined in the claims.

Reference is to be had to the accompanying drawings, forming a part of this specification, in which similar characters of reference indicate corresponding parts in all the figures, and in which—

Figure 1 is a central vertical section through a carbureter constructed in accordance with my invention; Fig. 2 is a central

vertical section taken at right angles to the plane of Fig. 1; Fig. 3 is a top plan view of the carbureter; Fig. 4 is a transverse section on the line 4-4 of Fig. 1; Fig. 5 is a view similar to a portion of Fig. 2, showing 60 the throttle valve detached; and Fig. 6 is an end view of the auxiliary air intake connections and throttle controller.

In the specific form of carbureter illustrated in the accompanying drawings, I employ a substantially cylindrical spun metal casing 10, having the bottom thereof formed integral with the sides and having the top formed by a cast metal plate 11. The plate is formed integral with an upper wall 12 and two concentric substantially vertical walls 13 and 14. Between these four walls is formed an annular air chamber 15, constituting an air distributing conduit or passage, and connected to an air supply pipe 16 leading from source of air, preferably air which has been previously heated. Within the casing are arranged a plurality of radially-disposed vertical plates 17, preferably formed of sheet metal and extending from adjacent the under surface of the top plate 11 to adjacent the bottom of the casing. The outer edges of the plate lie closely adjacent the peripheral wall 10 of the casing, but their inner edges are spaced apart to leave a central annular compartment 18. Each plate is inclosed in a flattened tubular sleeve 19, of fabric constituting a form of wick and serving to draw the liquid fuel from the lower portion of the casing upwardly toward the top of the casing by capillary attraction. The plates 17 serve inwardly toward the top of the casing by capillary attraction. The plates 17 serve in position. The lower edges of the plates 17 may be supported in any suitable manner, as, for instance, by an annular horizontally-disposed plate 20, and they are held against lateral displacement by the air pipes herein-after referred to. At the inner edges of the plates they may be kept apart by small metal clips 21, engaging with the fabric at one or more points along the length of the edge of the plate.

For delivering liquid fuel to the casing and maintaining the level of the liquid substantially constant, I provide the bottom of the casing with a threaded opening normally closed by a plate 22. This plate has a central aperture 23 therethrough and surrounding the aperture is a boss 24. To the boss 119

may be connected a liquid delivery pipe 25 by any suitable form of coupling 26. Within the boss 24 and held in place by the pipe 25, I employ a screen for preventing impurities and solid particles from passing into the casing with the liquid. In order to give the screen the maximum surface and to prevent it from becoming clogged by the accumulation of impurities, the screen is 10 preferably formed of a multiplicity of connecting conical portions. As shown, there is employed an outer truncated conical portion 27 having its periphery secured in place intermediate the ends of the boss 24 and the 15 end of the pipe 25, and at the smaller end of this truncated conical portion is an inner and inverted conical portion 28. The two conical portions together present a large surface through which the liquid may pass 20 and reduces to a minimum the liability of any clogging by the accumulation of solid particles.

At the inner end of the aperture 23 is a valve seat for receiving a vertically-movable valve 29 and encircling the valve stem 30 of said valve is a float 31. Below the float are levers 32 fulcrumed on bosses extending upwardly from the plate 22 and having their outer ends pivotally connected 30 to the float and their inner ends connected to the valve, whereby as the liquid accumulates within the lower portion of the casing the float may rise to force the valve downwardly against its seat and prevent the further admission of liquid. The float is somewhat smaller than the plate 22 and is preferably inclosed within a small casing 33 carried by the plate 22. This casing also serves as a guide for the upper end of the 40 valve stem 30. As all of these parts are smaller than the opening in the bottom of the casing, and as they are all carried by the plate 22; it is evident that by unscrewing this plate and removing it from the main 45 casing, the valve, float, casing 33, levers 32, and screens can be removed without disassembling the remainder of the carburetor.

The air which is admitted through the intake pipe 16 to the annular passage or conduit 15 is permitted to escape through a plurality of nozzles in the casing 10 adjacent the bottom thereof and beneath the liquid level. These nozzles are preferably formed by a plurality of small tubes 34, each having 55 its upper end extending through the top plate 11 of the casing and having its lower end disposed adjacent the bottom of the casing but bent upwardly so as to discharge beneath the surface of the liquid and toward 60 said surface. These tubes are preferably arranged in annular rows, as many rows being provided as necessary to give the desired cross sectional area of air outlet. The tubes are disposed between the plates 17 and the 65 tubes serve not only to deliver air but to hold

the plates in their spaced relationship. The liquid within the casing is drawn up by the fabric 19 covering the plates and the air, due to the suction of the engine, is drawn from the annular chamber 15 down through the 70 liquid and over the surface of the moistened fabric. The air thus becomes thoroughly charged with the vaporized liquid before escaping from the casing. In order to insure the uniform delivery of air over the surface 75 of the plates, I provide a series of baffles within the center chamber 18. These baffles have a series of small apertures over the surface thereof from the top to the bottom, so that the air escaping from the nozzles will 80 not rush directly to the lower portion of the chamber 18 but will pass upwardly between the plates and enter the chamber 18 at different points along its length. The specific form of baffle illustrated involves a plurality of tubular sheet metal sections 35 telescoped to form a continuous tube, and each having an outwardly-extending baffle or annular flange 36. Beneath each annular flange I provide an annular row of slots or apertures 90 37, through which the air may pass. Any liquid mechanically carried along with the air will be interrupted by the baffles and will collect on the annular flanges and drip back into the lower portion of the chamber. The 95 inner edges of the plates 17 are spaced away from the edges of the baffles or flanges so that none of the liquid in dripping from one flange to another will come into contact with the plates. Should the liquid travel 100 down the edges of the plates, some of it might be blown across to the baffles and through the openings 37. At the lower end of the series of baffle sections 35, is a terminal baffle section 38, having a closed end so 105 that none of the air can enter at the bottom of the series but all must pass through the openings 37. A spring 39 may be employed for partially supporting the series of baffles from the top of the float casing 33, and for holding the parts rigid against jarring or rattling.

The annular wall 13 which forms the inner side of the annular air inlet passage 15, also forms the wall of a vertical outlet passage 40, through which the explosive mixture escapes from the center of the series of baffles. Within this passage may be provided an upwardly-opening check valve 41 supported in any suitable form of guide 42 115 and preferably seating in the opening through the center of the plate 11. Rigidly secured to the top of the plate 12, at the center thereof and directly over the outlet passage 40, is a throttle valve casing 43 for 120 controlling the escape of explosive mixture from the casing and also for controlling the dilution of the explosive mixture by outside air. The casing is substantially tubular in 125 form with a horizontal axis, and is provided 130

with an opening 44 in its under side communicating with the passage 40 and connected to a conduit 45 for delivering the diluted explosive mixture to the engine or 5 other point of disposal. At the end of the valve casing opposite to the outlet 45, is an auxiliary air inlet, and in the top of the casing opposite to the inlet 44 is a second auxiliary air inlet. Within the casing is a 10 hollow, cylindrical rotatable throttle valve 46, having openings corresponding to the openings in the casing. One end of the throttle valve is open directly to the conduit 45 and within the valve casing adjacent the 15 outlet end from the throttle valve are a plurality of plates 47 for giving the explosive mixture a whirling motion as it emerges from the end of the throttle valve and enters the conduit 45. These plates are sub- 20 stantially radially-disposed, but each is inclined at a slight angle longitudinally of the conduit to produce the desired result. The throttle valve at the end opposite to the outlet conduit 45, is provided with an out- 25 wardly-extending arm 48 carrying a spring-pressed catch 49 in engagement with a series of notches in the periphery of an end plate 50 rigidly secured to the throttle valve casing. This end plate along the upper portion 30 thereof is spaced from the end of the casing proper to leave room for the arm 48, so that the latter may swing in an arc to rotate the throttle valve. The plate 50 is provided with a central aperture 51 and secured 35 to the outer surface of the plate and covering this aperture is a hood 52 provided with a conduit 53 leading from one side thereof to the main air delivering conduit 16. Thus air heated from any suitable source may be 40 delivered through the conduit 16 to the main casing of the carburetor, and a small portion of the air may be deflected from the conduit 16 through the conduit 53 to the hood 52 and thence into the throttle valve to di- 45 lute the explosive mixture. The delivering of air to the auxiliary air intake from the same source as the air delivered to the main body of the carburetor, constitutes an im- 50 portant feature of my invention.

For controlling the auxiliary air intake, the throttle valve is provided with an opening 54 registering with the opening 51 in the plate 50, and against the inner surface of the end of the throttle valve and covering this opening is a valve plate 55. The valve plate is carried by a stem 56 and is normally pressed against its seat by a spring 57. The valve stem is threaded through a collar 58 and by rotating the valve stem the 55 tension of the spring 57 may be varied to vary the suction pressure required to open the valve. It is of course understood that the valve plate slides on the valve stem. The collar 58 preferably extends through an opening in the hood 52 and is rigidly sup-

ported from the end of the throttle valve by two arms 59, 59, one of which is shown in Figs. 2 and 5, and both of which are shown in dotted lines in Fig. 6. At the outer end of the valve stem is a head 60, by means of 70 which the valve stem may be adjusted, and surrounding the valve stem and in engagement with the outer end of the collar 58 is a thumb nut 61 serving to lock the valve stem in position. The valve 55 as above indicated, constitutes an auxiliary air intake for diluting the explosive mixture, but this valve is designed to operate only at medium or high speeds. For diluting the mixture at low speeds, I provide the valve with a slot 80 75 85 90 95 100 105 110 115 120 125 130 62 in the wall thereof opposite to the main intake, and the casing is provided with an opening corresponding to the slot, but of considerably greater dimension lengthwise of the throttle valve. The valve casing at opposite ends of the opening therein, has lugs 63 and 64, between which is mounted a slide 65 for varying the effective size of the opening in the throttle valve. The slide is movable lengthwise of the casing between the lugs 63 and 64, and is so constructed that when in engagement with the lugs 64, the entire opening 62 is uncovered, while when the slide is in engagement with the lug 63, the opening is entirely closed. For varying the position of the slide, a threaded rod 66 is provided extending through the two lugs and having threaded engagement with the slide. By rotating the rod, the slide is moved longitudinally. A spring 67 is preferably mounted between one end of the rod and the outer surface of the lug 64, and preferably engaged by a flange 68 on the rod, so that a jarring action will not tend to rotate the rod. The spring also permits the rod and slide to be moved longitudinally to automatically vary the size of the air inlet 62 without rotating the rod, thus when the engine is running the rod may be moved longitudinally to partially close the opening, and the effect of this on the speed of the engine, may be noted. If it tends to slow down the engine, the rod may be rotated to open the slide to a further extent, while if it tends to increase the speed of the engine, the rod may be rotated to hold the slide in the new position. The circumferential length of the opening 62 is exactly equal to the circumferential length of the main inlet opening at the opposite side of the throttle valve, so that as the throttle valve is rotated, the main inlet and the auxiliary inlet 62 are opened or closed to exactly the same extent, and the relative cross sectional area of the main inlet and the auxiliary inlet remains constant irrespective of the position of the throttle.

For varying the size of the main inlet to the throttle valve, a slide 69 may be movable longitudinally of the throttle valve to

vary the length of the opening. Mechanism may be provided for operating this slide similar to that employed for operating the slide 65. As shown, a threaded rod 70 terminates in a lug 71 at the outlet end of the throttle and has threaded engagement with a lug 72 carried by the slide. The outer end of the rod terminates outside of the valve casing in a head 73, whereby the rod may be readily rotated to move the slide longitudinally. The slide may be normally held against movement by a spring 74 and may be guided by slot-and-pin connections 75 to the interior of the throttle valve. Neither the movement of the slide 65 nor the slide 69 varies the size of the openings in the throttle valve circumferentially thereof, but varies said openings longitudinally of the throttle valve. Thus the slides vary the percentage composition of the mixture for any particular position of the throttle, but the movement of the throttle varies only the amount and not the composition of the mixture. The throttle valve 25 may carry a series of plates 76 disposed substantially radially and arranged about the inlet opening 54, and each set at a slight angle, so as to give the air entering past the automatic air inlet valve 55, a rotary or whirling motion. A screen 77 may be provided for preventing the impurities from passing from the pipe 16 into the annular passageway 15, and a lug 78 having an adjustable stop 79 may be provided for 35 limiting the position of the arm 48 and the throttle valve.

Various changes may be made in the construction of my improved carbureter and within the scope of the appended claims, 40 without departing from the spirit of my invention.

Having thus described my invention, I claim as new and desire to secure by Letters Patent:

45. 1. In a carbureter, a casing, a plurality of vertically-extending plates extending from adjacent the bottom to adjacent the top of said casing forming a plurality of separate passages, a valve-controlled liquid inlet at the bottom of said casing, a float for controlling said valve, an air-delivery passage extending over a portion of the top of said casing, an air inlet at the top of said casing, and a plurality of air tubes 50 extending through each of the separate passages downwardly from said air-delivery passage and terminating beneath the level of the liquid within said casing and intermediate said plates.
55. 2. In a carbureter, a substantially cylindrical casing, a plurality of vertically-disposed plates spaced apart and radially disposed within said casing, a fabric covering for each of said plates, means for delivering a liquid to said casing and controlling 60

the normal liquid level; and a radially-disposed row of air-inlet pipes terminating intermediate said plates.

3. In a carbureter, a substantially cylindrical casing, a plurality of vertically-disposed plates spaced apart and radially disposed within said casing, a fabric covering for each of said plates, means for delivering a liquid to said casing and controlling the normal liquid level, a radially-disposed row of air-inlet pipes terminating intermediate said plates and below the normal liquid level, and an air-delivery passage delivering to each of said pipes. 75

4. In a carbureter, a casing, plates spaced apart within said casing, a sleeve about each of said plates adapted to absorb liquid, means for delivering liquid to said casing at the lower edges of said sleeves, an air delivery conduit extending across the top of said casing, and branch pipes leading therefrom between said plates, and having their lower ends terminating adjacent the lower edges of said sleeves and delivering upward over the surface of said sleeve-covered plates, whereby the liquid on said sleeves is vaporized. 85

5. In a carbureter, a casing, an annular row of radially-disposed plates forming a plurality of passages therebetween, means for delivering a liquid to said casing at the lower end of each of said passages, a tubular fabric sleeve inclosing each of said plates and terminating at its lower end within said liquid and means directing air to said fabric sleeves. 95

6. A carbureter having a casing provided with an outlet opening, a hollow, cylindrical valve controlling said outlet, a plurality of radially-disposed plates within said casing, 105 means for delivering a liquid to said plates, means for delivering air to said casing intermediate said plates and adjacent the lower end of said casing, and a sleeve concentric with said casing at the center thereof and having a plurality of passages through which the air may escape to said valve. 110

7. A carbureter having a casing, a sleeve disposed therein and concentric thereto and formed of a plurality of separate telescopic sections, each having an aperture therethrough, a plurality of radially-disposed plates surrounding said sleeve, means for delivering a liquid to the surface of said 115 plates, a plurality of air inlets adjacent the lower end of said casing and intermediate said plates, and a mixture outlet at the top of said carbureter and communicating with the upper end of said sleeve. 120

8. In a carbureter, a casing, a perforated plate closing the top of said casing, a second plate within said casing and supported from said first-mentioned plate, a plurality of vertically-disposed radially-arranged 125

fabric-covered plates intermediate said first and second-mentioned plates and supported thereby, and a plurality of tubes carried by said first-mentioned plate and extending downwardly intermediate said radially-arranged plates, said plates and tubes being connected together whereby they may be removed from the casing in assembled form.

In testimony whereof I have signed my name to this specification in the presence of 10 two subscribing witnesses.

MATHIAS WEIWODA.
